Claims priority, application France May 19, 1954

8 Claims. (Cl. 202—57)

The present invention relates to the purification of 15 acrylonitrile.

It is known that acrylonitrile, and especially that which is obtained by the combination of acetylene with hydrocyanic acid in the presence of a catalyst, contains in the unrefined state impurities of various kinds.

The most troublesome of these impurities are the dienic compounds, that is to say the compounds comprising two double carbon-carbon links in the position α . In the first place, some of these compounds, by reason of their physical and chemical characteristics, are particularly difficult to separate from the acrylonitrile. On the other hand, the dienic compounds, even when they are only present as traces, affect the properties of the polymers manufactured from acrylonitrile, tending in particular to make them insoluble.

Amongst the dienic compounds, it is more particularly divinyl-acetylene and cyano-butadiene 1.1.3. which are concerned.

The present invention relates to a particularly simple and effective method of destroying these dienic compounds.

This method consists in acting upon the acrylonitrile to be purified with nitrogen tetroxide, using a quantity calculated to destroy the dienic impurities; the acrylonitrile is then separated by distillation from the mixture thus obtained.

It is already known that nitrogen tetroxide, having the formula N_2O_4 , may be added to the double carbon-carbon links, giving, furthermore, fairly complex mixtures. On the other hand, it could not in any way be foreseen that it was possible, by the action of nitrogen tetroxide, to destroy the dienes up to the last traces, whilst leaving the acrylonitrile practically unaffected.

The method of carrying the invention into effect is particularly simple. It is sufficient to introduce the necessary quantity of nitrogen tetroxide, either in the gaseous form or as a liquid, under the surface of the acrylonitrile at ambient temperature. The operation may be effected either on successive charges of acrylonitrile contained for example in a tank provided with an agitator or in a continuous manner by introducing the nitrogen tetroxide into a flow of acrylonitrile.

The quantity of nitrogen tetroxide to be used will depend naturally upon the quantity of impurities contained in the acrylonitrile. If the quantity introduced is greater than that which is exactly required, the supplement will react with the acrylonitrile, but it has been found that it is useless to add any appreciable excess of reagent and that, by adding the quantity of nitrogen tetroxide which is proportional to the quantity of dienes, the latter are completely destroyed without affecting the acrylonitrile.

The great affinity of nitrogen tetroxide for dienes is clearly shown by the production of heat which takes place as soon as the reagent is introduced. It may be necessary to cool the locality in which the reaction takes place, but in practice, the operations are confined to a medium which contains as a maximum only a small percentage

2

of dienes so that the production of heat does not result in a troublesome increase in temperature.

After the nitrogen tetroxide has been introduced, it is preferable to wait for a certain time, for example 15 minutes to one hour, in order to give the reaction time to complete itself. The purified acrylonitrile can then be separated out by distillation.

The acidity which is produced by the reaction may be neutralised before the distillation process. Although this operation is not absolutely essential, it may be desirable from the point of view of corrosion.

It is an advantage to separate out the acrylonitrile by carrying it away with steam. On the one hand, there is thus obtained with good efficiency an acrylonitrile which is particularly pure and which only requires to be dried. On the other hand, the reaction products of the nitrogen tetroxide which remain in the end reactions are liable to be decomposed more or less violently if they are over-heated after they have been concentrated by the distillation of the acrylonitrile.

The examples given below will emphasize the remarkable results obtained by the use of the invention.

Example 1

In a vessel provided with an agitator and a thermometer, there were placed 200 grams of acrylic nitrile containing 0.64% by weight of divinyl-acetylene to which there was introduced for a period of 20 minutes 3 grams of nitrogen tetroxide in liquid form and having a degree of purity of 99.5%. During this introduction, the vessel was cooled by a current of water at 15°C. The reaction was then allowed to proceed for half an hour, the acrylonitrile being then separated out from the products formed by carrying it away with steam. After decantation and drying of the acrylic nitrile, analysis showed that it contained less than 0.0003% by weight of divinyl-acetylene.

Example 2

When treated under the same conditions as in Example 1, but with only 2 grams of nitrogen tetroxide, the acrylic nitrile, which initially contained 0.64% of divinyl-acetylene, only contained 0.022% by weight.

Example 3

Using the same apparatus and following the same method of operation, 500 grams of acrylic nitrile containing 0.89% by weight of divinyl-acetylene and 0.5% by weight of cyano-1-butadiene-1.3 were treated with 7.5 grams of nitrogen tetroxide which was added in 20 minutes. After carrying-off with steam, decantation and drying, the acrylic nitrile contained less than 0.0008% of divinyl-acetylene and less than 0.001% of cyano-butadiene.

What we claim is:

1. A method of purifying acrylonitrile from dienic compounds contained therein, comprising the step of reacting said acrylonitrile with nitrogen peroxide in quantity sufficient to destroy said dienic impurities, whereafter the acrylonitrile is separated out by distillation.
2. A method of purifying acrylonitrile from dienic compounds contained therein, comprising the step of reacting said acrylonitrile with nitrogen peroxide in quantity sufficient to destroy said dienic impurities, whereafter the acrylonitrile is drawn off by steam.
3. A method of purifying acrylonitrile from dienic compounds contained therein, comprising the step of introducing nitrogen tetroxide below the surface of said acrylonitrile, in quantity sufficient to destroy said dienic impurities, whereafter the acrylonitrile is separated out by distillation.
4. A method as claimed in claim 3, in which liquid nitrogen tetroxide is used.

5. A method as claimed in claim 3, in which gaseous nitrogen tetroxide is used.

6. A method of purifying acrylonitrile from dienic compounds contained therein, comprising the steps of reacting said acrylonitrile with nitrogen peroxide in quantity sufficient to destroy said dienic impurities, and neutralising the reaction mixture, whereafter the acrylonitrile is separated out by distillation.

7. A method of purifying acrylonitrile from dienic compounds contained therein, comprising the steps of reacting said acrylonitrile with nitrogen peroxide in quantity sufficient to destroy said dienic impurities, and leaving the reaction mixture at rest during about 15 to 60 minutes, whereafter the acrylonitrile is separated out by distillation.

8. A method of purifying acrylonitrile from dienic

compounds contained therein, comprising the steps of reacting said acrylonitrile with nitrogen peroxide in quantity sufficient to destroy said dienic impurities, leaving the reaction mixture at rest during about 15 to 60 minutes, and neutralising the reaction mixture, whereafter the acrylonitrile is separated out by distillation.
